UNITED STATES PATENT OFFICE

147,262

DESIGN FOR A SHOESHINE CABINET

William D. Dunn, Linden, N. J.

Application March 16, 1946, Serial No. 127,584

Term of patent 14 years

(Cl. D58—4)

To all whom it may concern:

Be it known that I, William D. Dunn, a citizen of the United States, residing at Linden, in the county of Union and State of New Jersey, have invented a new, original, and ornamental Design for a Shoeshine Cabinet, of which the following is a specification, reference being had to the accompanying drawing, forming a part thereof.

Fig. 1 is a perspective view of a shoeshine cabinet, showing my new design, the cabinet being shown as it appears when not in use.

Fig. 2 is a perspective view of the cabinet shown in Fig. 1, as it appears when in use as a support for a shoe to be shined.

The upper central element of the cabinet is pivoted on its longitudinal axis and is provided at one side of its axis with a handle portion, as shown in Fig. 1, and at the opposite side of its axis with a shoe support, as shown in Fig. 2. The element is adapted to be turned selectively to either of the two positions shown.

I claim:

The ornamental design for a shoeshine cabinet, as shown and described.

WILLIAM D. DUNN.
